UNITED STATES PATENT OFFICE.

WILLIAM T. MALONEY, OF TRENTON, NEW JERSEY, ASSIGNOR TO ROBT. H. INGERSOLL & BRO., A JOINT-STOCK ASSOCIATION OF NEW YORK.

BANKING-PIN FOR WATCHES, CLOCKS, AND THE LIKE.

1,144,857.

Specification of Letters Patent. Patented June 29, 1915.

Application filed January 8, 1914. Serial No. 811,043.

To all whom it may concern:

Be it known that I, WILLIAM T. MALONEY, a citizen of the United States, residing at Trenton, New Jersey, have invented certain new and useful Improvements in Banking-Pins for Watches, Clocks, and the like, of which the following is a specification.

It is the object of my invention to provide a banking pin of such construction that it can be made at a low cost and also one that will not get out of adjustment and when set at the factory can not be altered by unskilled repairers.

15 The invention is shown in the accompanying drawings, in which—

Figure 1 is a plan view of an escapement lever with the banking pins in relation thereto; Fig. 2 is a side elevation of the 20 banking pins mounted in their supporting plate and showing the escapement lever in section; Fig. 3 is a plan view of a modified form of banking pin with the escapement lever associated therewith; Fig. 4 is a 25 side view of the banking pins of Fig. 3 mounted in their supporting plate showing the escapement lever in section; Fig. 5 shows interchangeable banking pins formed 30 from sheet metal; Fig. 6 shows interchangeable pins of wire.

Referring to Figs. 1 and 2, the banking pins 5 are formed from round wire bent up into U-shape, as shown in Fig. 2, the two ends of this U-shaped wire extending from 35 the supporting plate 6 into proper position for coöperating with the escapement lever 7 in the usual manner. These banking pins are intended to limit the stroke or swing of the escapement lever to a predetermined degree, and by the construction shown the 40 banking pins maintain their position in relation to the escapement lever without liability of becoming altered in their adjustment by accident or by the work of an unskilled repairer.

Heretofore screws have been used having cylindrical projections to serve as banking pins, the screws being capable of being turned so that the distance between the sides 50 of the cylindrical portions which are eccentric to the axis of the screw may be changed. It is the intention in the use of banking pins to adjust them accurately at the factory and after they have been set 55 they are to remain permanently in this ad-

justment, but with the screw form above mentioned it has been possible, either through accident or by the work of a watch repairer, to disturb the adjustment and thus alter the stroke of the escapement lever 60 and throw the watch out of time. It has also been proposed, as shown in the patent of De Long #815,271, of March 13, 1906, to have interchangeable banking screws, said screws having banking portions of plain 65 cylindrical form concentric with the axis of the screw threaded portions but of different diameters so that the distance between these banking portions would remain fixed when once adjusted at the factory. I accomplish 70 the same result in a simpler and less expensive manner by the use of a U-shaped wire which provides the two banking portions in one piece and which enables the assemblage to be made quickly, it being only 75 necessary to thrust the U-shaped member through the openings formed in the supporting plate to locate and properly position the banking portions in place, both banking pins being handled as one body. 80 The banking pins can be produced rapidly in automatic machinery from a continuous length of wire. The banking pins can be made with different width of space between 85 them adapted to different escapement movements.

It will be noticed from Fig. 2 that it is only necessary to thrust the U-shaped member through the openings in the supporting plate to get the proper adjustment of the 90 banking pins, both as to their width or distance apart and also as to the extent to which they project from the supporting plate, the connecting cross piece 8 acting as a stop by coming in contact with the face of 95 the supporting plate.

In Figs. 3 and 4 the main principles above set forth are also embodied but instead of making the banking pins from a round wire they can be stamped out of sheet metal in a 100 U-shape, no subsequent bending being required.

In Fig. 5 I show a series of interchangeable banking pins having different widths between the inner sides of the portions 105 against which the escapement lever strikes, the exterior widths being the same in all the forms of the series mentioned. These banking pins, instead of being seated each in a pair of openings in the movement plate, 110

are seated in a single opening formed large enough to take the entire U-shaped pin, and this enables the banking pins to be interchanged to secure the proper adjustment of the movement. The wire form of banking pin is adapted for low grade watches, while the form shown in Figs. 4 and 5 is adapted for high grade watches. It will be understood that the pin of U-shape blanked out of sheet metal instead of being inserted in a single opening as shown in Fig. 4, may be inserted with its prongs in a pair of openings in a manner like that shown in Fig. 2.

In all the forms the pin is driven to a point which may be determined by the cross bar, *i. e.* in Fig. 2 by the cross bar coming against the plate and thus acting as a stop, or in Fig. 4 by the cross bar coming flush with the surface of the plate. The feature of interchangeability described in connection with the pins blanked out of sheet metal also may be secured in connection with banking pins made of wire bent into the approximate form shown in Fig. 6, in which the main body of the pin is of a width to fit the opening in the plate, whereas the prongs of the pin will be differently spaced apart so that the pin, having the proper distance between its prongs to suit the stroke of the escapement lever, may be selected and inserted in the plate.

It will be observed that my banking pin has plain prongs (and this is meant to apply to Fig. 6 as well as all the other forms) in the sense that they are free from outside projections or adjustable screws, such as would defeat one of the objects of my invention, which is to provide a banking pin in which by the simple act of thrusting it through the supporting plate it will be set to act, with both of its prongs in proper position, no individual setting of the prongs or banking members being required.

Where in the foregoing description or the appended claims I refer to a banking pin of U-shape, I employ this term in a generic

sense to refer to the general shape of the banking pin having two prongs connected by a piece extending between them.

I claim as my invention:

1. A banking pin of U-shape having prong portions to be thrust through a supporting plate and held by contact with the said plate.

2. In combination in a watch, an escapement lever, a supporting plate and banking pins consisting of one piece in U-shape providing two banking portions extending through the plate and projecting therefrom on one side and receiving the escapement lever between them, substantially as described.

3. In combination in a watch, an escapement lever, a supporting plate and banking pins consisting of one piece in U-shape with the two banking portions extending through and projecting from the plate on one side, the position of the pins in the plate being determined by the relation of the cross piece to the surface of the plate, substantially as described.

4. Interchangeable banking pins for watches of U-shape having the same exterior width at the portions that bear in the supporting plate and different interior widths at the points of contact of the escapement lever, substantially as described.

5. In combination an escapement lever, a supporting plate having an opening, and banking pins of one piece in U-shape inserted in said opening, said opening being adapted to receive U-shaped pins of one exterior width but of different interior widths at their points of contact with the escapement lever.

In testimony whereof, I affix my signature in presence of two witnesses.

WILLIAM T. MALONEY.
